UNITED STATES PATENT OFFICE.

LOUIS JAMES MITCHELL, OF DINUBA, CALIFORNIA.

COLLAPSIBLE ASSORTING RACK.

Application filed December 26, 1922. Serial No. 609,011.

The present invention refers to collapsible assorting racks and has particular reference to a rack intended to be used in post offices for the distribution and assorting of mail. It is intended to provide an assorting rack of the character described that after having received the mail may be conveniently collapsed and placed into the vehicle of a mail carrier, who then may withdraw the mail as he reaches the house of each addressee. My assorting rack is particularly adapted to be used for rural delivery. It comprises a plurality of partitions or pigeon holes connected in such a manner that they may be readily secured to a stationary support, the various pigeon holes being marked with the names of the various persons likely to receive letters through the post office. The mail may thus be distributed immediately upon arrival and at certain intervals the mail carrier may take the whole device, collapse the same so as to reduce the space necessary for holding it, and place it in his vehicle without disturbing the arrangement of the various papers, letters, et cetera. The mail will thus be ready for immediate withdrawal whenever the house of the addressee is approached by the mail carrier.

The preferred form of my invention is illustrated in the accompanying drawing in which Figure 1 shows a front view of my device; Figure 2 a side view of the same; Figure 3 a top plan view; Figure 4, a front view of the device in its collapsed condition; Figures 5 and 6 perspective detail views illustrating the manner of fastening my device to a stationary support. While I have shown only the preferred form of the invention it should be understood that various changes or modifications may be made within the scope of the claims hereto attached without departing from the spirit of the invention.

My device consists of a plurality of floors or platforms (1) preferably of rectangular shape disposed one above the other and joined together by flexible means (2). The latter comprises preferably a plurality of cords passing through the marginal portions of the various platforms and provided with knots (3) for supporting the latter. It will be seen that this manner of supporting the platforms allows a limited freedom of motion for the platforms in case one of the pigeon holes formed by the same should require more space than the

one next above. This array of platforms may be supported in any suitable manner in an operative position. In the preferred form shown in the drawing the top member (4) of the device is provided with guides (6) adapted to receive a horizontal plate (7) extending from a vertical support (8). The horizontal plate is shown in detail in Figure 5 and is provided with a downwardly extending flange (9) adapted to engage a guide member (11) of the same proportions secured to the stationary support (8) by any suitable means as by the screws (12). The bottom member (13) is held in its lowermost position by hooks (16) extending laterally from the support (8) and a single vertical hook (20) secured in the bottom plate and adapted to be turned to engage the top face of the lower plate and to hold the same. The distance between the bottom support and the top support is such as to correspond with the length of the various cords holding the platforms together so that when held in its operative position the device assumes a semi-rigid character.

The front end of each plate is provided with a numeral or other identifying marks, as for instance, the various names of the persons to whom mail is to be delivered. The bottom plate (14) is hinged to the stationary support (8) as shown at (17) so that it will automatically drop when the assorting rack is removed.

While in this operative position the mail is assorted and distributed into the various pigeon holes formed by my device. If the pigeon hole made to receive the mail of a certain addressee is not large enough, the platform above the same may be lifted, whereby the size of the pigeon hole is increased at the expense of the one next above, which latter again may be increased in size if the space reserved for the same is not large enough. Assuming now that all of the mail has been distributed, some of the pigeon holes being filled, some partly filled, and some empty, and it is desired to take the rack to the vehicle of the mail carrier, it would be extremely inconvenient to manipulate the rack by merely taking it off of its support and transferring the same to the vehicle, and I, therefore, provide convenient means for first collapsing the rack so as to form a compact unit whereby the danger of some of the letters or papers dropping out of the rack is removed. This

means consists of two additional cords (18) secured to the lower platform as shown at (19) and passing through all the other platforms with their free ends secured to a 5 spindle (21) supported in standards (22) rising from the top member (4) in spaced and parallel relation. A suitable crank handle (23) is provided by means of which the spindle (21) may be rotated and the 10 cords wound upon the same. A ratchet wheel (24) is keyed to the spindle and its teeth engage with a pawl (26) pivotally supported in operative proximity to the ratchet wheel, whereby the spindle (21) is 15 locked against a reverse motion.

While the particular construction of the device allows of many slight changes and modifications, and while various operators will probably develop various convenient 20 ways for handling the device, I wish to suggest the following method: A vertical support (8) is preferably secured on the center of a narrow table so that racks may be secured on both sides of the same. The top member of the rack is engaged with the plate (7) whereby the same is supported in a horizontal position, whereupon the pawl (26) is disengaged from the ratchet (24) which causes the lower platforms to drop 25 into their respective positions. The lowest member is then secured to the bottom member (14) which should be distant from the top support sufficiently far to make it necessary to slightly stretch the cords so as 30 to give some rigidity to the device. The mail may now be assorted and if a desired number of letters, papers, et cetera, has accumulated, the rack is removed in the following manner: First, the bottom member 35 40 of the rack is cleared of the hooks (16)

whereupon the shaft (21) is rotated by means of the crank handle (23), which causes first the lowest platform, and then the other platforms in their successive order, to be pulled upwardly until the whole 45 device forms one compact unit with the various letters and papers clamped between the platforms. In this condition the device is locked by the pawl and ratchet engagement and slid off the plate (7). It is then 50 transferred to the mail carrier's vehicle, who is now ready to start his journey, it being assumed, of course, that a plurality of racks are employed to handle all the mail to be distributed. As the mail carrier 55 reaches the house of an addressee he only need to take out the letters and papers contained in that particular pigeon hole without disturbing any of the remainder of the mail. 60

I claim:

A collapsible assorting rack comprising a plurality of platforms disposed one above the other, flexible means passing through the platforms having supports for the platforms incorporated therein and allowing the platforms to assume spaced relation so that articles may be placed on the same, means for horizontally supporting the top platform, and means mounted on the upper 65 platform for pulling the lowermost platform upwardly whereby all the platforms and articles are compressed into one uninterrupted unit, the platforms being supported on the flexible means with freedom 70 of vertical sliding motion allowing the space above one platform to be increased at the expense of the space above the next higher platform. 75

LOUIS JAMES MITCHELL.
